K. FORBES

DOOR LATCH

Filed Oct. 14, 1922

Inventor
Kingston Forbes
By his Attorneys,
Ward, Crosby and Smith

UNITED STATES PATENT OFFICE.

KINGSTON FORBES, OF FLINT, MICHIGAN.

DOOR LATCH.

Application filed October 14, 1922. Serial No. 594,433.

To all whom it may concern:

Be it known that I, KINGSTON FORBES, a citizen of the United States, and resident of Flint, county of Genesee, and State of Michigan, have invented certain new and useful Improvements in Door Latches, of which the following is a specification.

The invention relates to improvements in door latches and particularly to latches adapted for use in connection with automobile doors. An object of the invention is the provision of an improved and effective construction whereby hand operated means, rotatable in either direction and preferably of the hand lever type, is provided, to cause the actuation of a lever which retracts or otherwise operates the bolt. Another object is the provision of a device of the character referred to in which hand operated means adapted to be actuated from the outside, acts upon the said bolt retracting lever, at a point situated at one side of the pivot of the lever, while hand actuated means, operable from the inside, is adapted to act upon this lever at the opposite side of the pivot thereof, to cause the retraction of the bolt.

In the preferred embodiment of the invention a single lever is provided for retracting the bolt, the latter being spring pressed towards its operated position. This lever is normally engaged by the opposite ends of a curved arm pivoted intermediate its ends and adapted to be rotated in either direction by a hand lever on the outside of the door. Actuation of the hand lever in either direction serves to cause one of the ends of the curved arm to swing the bolt retracting lever in the proper direction to cause it to retract the bolt against the force of the spring. The ends of a similar curved arm, similarly pivoted, normally engage the opposite side of the bolt-retracting lever at points located on the opposite side of the pivot of the lever, this arm being operated, preferably by a hand lever, from the inside of the door, so that swinging the same in either direction will cause the retraction of the bolt. With such a construction, it may be noted, the two door handle levers will normally be held in desired angular positions such as horizontal positions because of the engagement of the opposite ends of the curved arms referred to with the lever, the latter being pressed against the ends of

these arms by suitable spring means. Further, a simple and effective construction is provided in which handle means, preferably of the hand lever type, and rotatable in either direction to retract the bolt, may be utilized.

The invention consists in the novel construction, arrangement and combination of parts hereinafter described according to the preferred embodiments thereof. The invention will be more particularly pointed out in the appended claims.

In order that the invention may be more clearly understood attention is hereby directed to the accompanying drawings forming part of this application and illustrating one form of apparatus embodying the invention. In the drawings Fig. 1 represents a front elevation of mechanism comprising the invention, partly shown broken away and partly in section, the bolt being shown as shot and the inside and outside operating hand levers being shown in their normal inoperative positions;

Fig. 2 is a similar view, the bolt being shown as retracted by operation of the outside hand lever;

Fig. 3 is a similar view, the bolt being shown as retracted by operation of the inside hand lever, and

Figs. 4 and 5 are sections taken respectively on lines 4—4 and 5—5 of Fig. 1.

Referring to the drawings, the supporting plate 1 carries the latch bolt 2, mounted to slide back and forth over the plate. The bolt is guided in its reciprocation by suitable means such as the casing comprising the top and bottom and side portions 3 extending from plate 1 or secured thereto in any suitable manner. The bolt is normally pressed into its operative or shot position by suitable spring means such as the coil spring 4 illustrated as mounted in position within the rear portion of the bolt casing, so as to bear against the rear surface of the bolt. It will be understood that plate 1 and the device carried thereby may be secured in position upon the door in any suitable or usual way, as by suitable screws extending through openings 5 in plate 1, into the inner face of the door, a suitable recess being provided within the door structure for the movement of the operating parts on the outer face of plate 1. Plate 1 is shown as provided with a flange 6 adapted

to be secured to the edge of the door, the nose of the latch bolt 2 extending through a suitable opening in this flange.

A lever 7 is pivotally mounted on the outside face of plate 1, that is the face of the plate which is directed towards the outside of the door, the pivot pin 8 on which the lever is mounted being, as shown, intermediate its ends. The lower end of this lever 10 extends through a suitable slot in the upper wall of casing 3 of bolt, 2, to bear against a shoulder 9 on the bolt, it being understood that the bolt is suitably formed or recessed as to permit the movement of the lower 15 end of lever 7 within the bolt casing 3. Accordingly oscillation of lever 7 in a counter-clockwise direction from the position shown in Fig. 1 to the position shown in Fig. 2, or Fig. 3, will result in the retraction of the 20 bolt within its casing against the force of spring 4.

Handle means for retracting the bolt, in the embodiment of the invention illustrated, comprises a hand lever 10 on the inside 25 of the door and a handle member 11 on the outside of the door. Hand lever 10 is provided at one end with a boss 12 to which is secured a pin 13 which extends through and is rotatably mounted in supporting 30 plate 1. A curved or inclined arm 14 is mounted on the outside face of plate 1 and secured to pin 13. Pin 13 may be provided with a squared portion 15 which extends through a similarly shaped opening in arm 35 14 so as to cause the arm to rotate with the pin when the latter is given a motion of rotation in one direction or the other.

Arm 14 is provided with upper and lower end portions 16, 16¹, both of which normally 40 engage against the adjacent, or right hand, edge of the upper vertically extending portion of lever 7, when hand lever 10 is in its normal horizontal position, as shown in Fig. 1. The pin 13 extends through and is secured to arm 14 at a point intermediate 45 the ends of the latter, as shown, the upper and lower portions of arm 14 being inclined or curved from the intermediate portion of the arm towards the adjacent portion of lever 7, so as to permit the engagement of 50 the ends of the arm with lever 7. Preferably a metal strap 17 is secured to plate 1 to extend over the intermediate portion of arm 14 to hold the latter in position against 55 the face of plate 1. A leaf spring 18 may, as shown, be secured to plate 1 and positioned to bear against an edge of lever 7 to press the opposite edge of the upper portion of the same firmly against the two end portions of arm 14 when the parts are in their 60 normal inoperative position.

With this construction it is obvious that bolt 2 may be retracted by swinging the inside hand lever 10 either downwardly from 65 its horizontal position, or upwardly from

such position. When the hand lever is swung downwardly, as shown in Fig. 3, the lower end portion 16¹ of arm 14 will engage the upper portion of lever 7 to cause the lower end of this lever to retract the bolt, as is shown in Fig. 3. Similarly when hand lever 10 is swung upwardly from its normal horizontal position the upper end 16 of arm 14 will engage lever 7 to retract the bolt. 75

The devices for retracting the bolt from the outside of the door may, as shown, be quite similar to the inside hand operated means. As shown, the hand bar 11 may be provided with a central boss 19 from which extends a spindle or pin 20 of square section, or having a squared portion, which extends through and is thus secured to the arm 21 at the intermediate portion of the latter. Arm 21 may be entirely similar to arm 14, arm 21 being provided with upwardly and downwardly extending end portions which are adapted to both engage against an edge of lever 7 when the hand lever or bar 11 is in its normal horizontal position. The ends of arm 21 engage against the edge of lever 7 opposite to the edge which is engaged by the ends of arm 14; since arm 21 is located below the pivot 8 of lever 7 while arm 14 is located above pivot 8, it is obvious 95 that oscillation of arm 21 in either direction will cause the retraction of bolt 2. Thus, as is shown in Fig. 2, handle bar 11 may be swung in one direction to cause the upper end of arm 21 to engage against and swing lever 7 into its bolt retracting position, while oscillation of handle bar 11 in the opposite direction from its horizontal position would cause the lower end of arm 21 to thus engage and swing lever 7. Arm 100 21 may be held in position against plate 1 by means of a suitable strap 22, similar to the strap 17, referred to above. It will be noted that the lower end portion of arm 21 extends into bolt casing 3 through the same slot in which the lower end portion of lever 7 extends. 105

It will be noted that arm 7 is preferably so arranged that its pivot pin 8 and the pivots 13 and 20 of handle lever 10 and handle bar 11 respectively are arranged in the same vertical plane. This may readily be accomplished by providing lever 7 with parallel upper and lower portions, against which arms 14 and 21 engage, these upper and lower portions being connected by an angularly extending portion 7¹. 115

It will be noted that an extremely simple, effective and compact arrangement is provided by the construction described. Rattling of the parts, when the device is mounted on the door of an automobile, or other vehicle, is prevented inasmuch as the lower end portion of lever 7 is normally pressed by spring 4 of the bolt against the 120 125 130

ends of arm 21, while spring 18 serves to press the upper portion of lever 7 against the ends of arm 14, when the parts are in their normal inoperative position.

5 It will be noted that the devices illustrated specifically as arms 14 and 21 constitute cam means, which normally engage lever 7 and are rotatable in either direction to operate the lever.

10 It should be understood that the invention is not limited strictly to the details of construction which have been particularly described, but that the same is as broad as is indicated by the accompanying claims.

15 What I claim is:

1. In a door latch, the combination of a support, a bolt movable horizontally thereon, a vertically extending lever pivoted intermediate its ends to said support and adapted to engage against the bolt to retract the same, cam means adapted normally to press against said lever at one side of the pivot thereof, on one side of the lever, cam means adapted normally to press against said lever at the other side of the pivot thereof, on the other side of the lever, each of the same being adapted, upon actuation, to swing said lever to retract the bolt, and hand means for operating said cam means.

20 2. In a door latch, the combination of a support, a bolt movable thereon, a lever pivoted intermediate its ends to said support and adapted to engage against the bolt to retract the same, cam means adapted normally to press against said lever at one side of the pivot thereof, on one side of the lever, cam means adapted normally to press against said lever at the other side of the pivot thereof, on the other side of the lever, each of the same being rotatable in either direction from its normal engaging position, to swing said lever to retract the bolt, and hand means secured to said cam means for rotating the same.

25 3. In a door latch, the combination of a supporting plate, a bolt slidably mounted thereon and having an abutment, a spring pressing said bolt forwardly, a lever pivoted intermediate its ends to said plate and having an end portion adapted to engage against said abutment to move said bolt in one direction against said spring, arms pivoted to said plate and adapted to engage said lever on opposite sides of the pivot thereof, one of said arms engaging said lever on one edge thereof opposite to the edge engaged by said abutment and the

other arm on the opposite edge thereof, a spring tending to press said lever against said second arm, and handle means for rotating either of said arms to move the bolt in the same direction.

4. In a door latch, the combination of a supporting plate, a bolt slidably mounted thereon, a lever pivoted intermediate its ends to said plate and having an end portion adapted to engage against and move said bolt in one direction, a pair of two armed levers pivoted intermediate their ends to said plate, both ends of one of the same engaging against one edge of said first named lever, at one side of the pivot thereof, and both ends of the other of the same engaging against the opposite edge of said first named lever, at the opposite side of the pivot thereof, when the parts are in a normal position, and handle means for operating either of said two armed levers to move the bolt in one direction.

5. In a door latch, the combination of a supporting plate, a bolt mounted for horizontal reciprocation thereon, a vertically extending lever pivoted intermediate its ends to said plate and having an end portion positioned to move said bolt in one direction, arms pivoted to said plate and adapted to engage said lever on opposite sides of the pivot thereof, one engaging said lever on one edge thereof and the other on the opposite edge thereof, the pivots of said arms being in vertical alignment, and handle means secured to the pivots of said arms.

6. In a door latch, the combination of a latch plate, a bolt slidably mounted thereon and having an abutment, a spring pressing said bolt forwardly, a lever pivoted intermediate its ends to said plate at a point above said bolt and having a portion engaging said abutment, and adapted to retract said bolt against said spring, a cam member mounted on said plate, normally engaging said lever at a point below the pivot thereof, on the side of the lever opposite to that engaged by said abutment, a cam member mounted on said plate, normally engaging said lever at a point above the pivot thereof, on the side of the lever opposite to that engaged by said first cam member, and hand means, for rotating said cam members to oscillate said lever to retract the bolt.

In testimony whereof I have signed my name to this specification.

KINGSTON FORBES.
